Primary Examiner — Jennifer Rivard(74) *Attorney, Agent, or Firm* — Wayne & Ken, LLC;
Tony Hom(57) **CLAIM**

The ornamental design for hair shaver, as shown and described.

DESCRIPTION

FIG. 1 is a perspective view of a hair shaver showing my new design.

FIG. 2 is another perspective view thereof;

FIG. 3 is a front side elevational view thereof;

FIG. 4 is a back side elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is enlarged view of the shave head and the portion of the handle in FIG. 4.

The left side view is a mirror image of the right side view. The broken lines shown in the figures are for the purpose of illustrating portions of the hair shaver, which form no part of the claimed design.
